UNITED STATES PATENT OFFICE.

JOSEPH V. CLARK, OF STEUBENVILLE, OHIO.

LUBRICATING DEVICE.

SPECIFICATION forming part of Letters Patent No. 779,690, dated January 10, 1905.

Application filed July 14, 1904. Serial No. 216,508.

To all whom it may concern:

Be it known that I, JOSEPH V. CLARK, a citizen of the United States, residing at Steubenville, in the county of Jefferson and State of Ohio, have invented certain new and useful Improvements in Lubricating Devices; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a new and useful improvement in an oil lubricating device designed and constructed with a view of utilizing the condensation of steam to force the oil contained in the reservoir into the steam-line supplying the steam-chest and cylinder on the engine.

In the accompanying drawings, forming a part of this specification, I have illustrated my invention by two views, in which—

Figure 1 is a vertical exterior view of my improved lubricator; and Fig. 2 is a vertical sectional view of the head portion of my lubricator, showing the passage-ways and communicating chambers formed therein.

Like numerals of reference designate like parts throughout both views, in which—

The numeral 1 represents the oil-reservoir, and 2 is an indicator-glass attached to the side and communicating with the interior of said oil-reservoir. 3 is a drain-valve in the bottom of the reservoir. Removably connected to said oil-reservoir is the head portion 4 of my lubricating device, in which are formed a number of communicating passage-ways for conducting the lubricant therethrough and thence into the steam-line supplying the valves on the engine. The first of these passage-ways 5 is formed in the neck of the head portion and constitutes an oil-chamber

from which the lubricant may be diverted in two different and distinct directions through said head. The first or main flow of the lubricant is through a communicating channel 6 or sight-feed line formed in an extension part

7, the flow being regulated by a valve-stem 8, 50 entering the neck portion through the chamber 5 at a point directly opposite the inner end of said channel 6. The lubricant after flowing or being forced through said channel passes upward through a jet 9, seated over 55 the outer end of said channel 6, and thence through the sight-glass 10, seated between said extension part 7 and a condensing-head 11, formed integral with a curved arm 12. The steam condensing in this head 11 fills 60 the sight-glass 10, and the entire body of oil being forced directly against the jet 9 prevents the latter from clogging and insures a constant flow through said jet. As the oil passes through the body of water contained in said 65 sight-glass and condensing-head and reaches the curved channel 13 it readily flows down the incline formed by the curved arm and is there caught up by the steam entering said head portion through the straightway passage 14 and from there carried to any point 70 on the engine to be lubricated.

Formed in the upper portion of the head directly over the chamber 5 and divided therefrom by a bridge-wall 15 is a steam-chamber 16, communicating with the straightway passage 14 and curved channel 13. Connected to the upper end of this chamber 16 is a condensing-tube 17, which passes down through the bridge 15, thence through the 80 oil-chamber 5, where it enters the oil-reservoir 1 and extends down nearly to the bottom thereof.

Connected to the top of the head portion is a nipple 18, engaging with the top of the condensing-tube 17 and held in position by a packing-nut 19.

Leading from the straightway passage 14 through the bridge-wall 15 is a by-path running parallel with said bridge-wall and communicating with the oil-chamber 5. This by-path affords an emergency-line for the lubricant in case anything should go wrong with the sight-feed line.

A controlling-valve stem 21 enters the 95 straightway passage 14 at a point directly opposite the by-path 20, having its seat in the same.

In filling the reservoir 1 oil is introduced through the plug 22, formed in the head portion.

In the operation of my improved lubricating device the reservoir is first filled with oil. The straightway passage 14 and nipple 18 being connected with the steam-line and the valve 8 being open, the condensation of steam in the tube 17 by the weight of gravity over 5 and above the equalization of boiler-pressure forces the oil contained in the reservoir through the channel 6 up through the jet 9, where it rises to the top of the water contained in the sight-glass and condensing-head 10 and is then carried off through the curved channel 13 into the chamber 16, where it mixes with the steam and is then carried to any point on the engine to be lubricated. Should the channel 6 or jet become clogged 15 with any foreign matter, then without interfering with the supply of lubricant to the engine the valve 21 is opened, and immediately by the same method as is employed in forcing the oil through the sight-feed line the lubricant will be forced into the straightway passage 14 direct through the by-path 20 and there be caught up by the steam and carried to the valve of the engine. The steam surrounding the tube 17 as it passes through the 20 chamber 16 will keep the condensation of steam therein in a heated state, and as this warm water passes through the oil-chamber 5 and into the reservoir it serves to retain the oil in a workable or liquid state, thus preventing 25 freezing or thickening of the same. By this system of preheating the oil contained in my lubricator I am able to use the heaviest and thickest of oils as lubricants, as they become thin and easily introduced through the valves 30 and passage-ways and into the steam-line under the method employed in my device.

My lubricator is applicable to any variety of engine utilizing steam and may be located at any desired and convenient point either on 45 the engine or at a reasonable distance therefrom, it being one of the features of my invention that the reservoir may be detached from the head portion and a larger supply-tank be used, thus avoiding the necessity of 50 frequent refilling.

Having thus fully shown and described my invention, what I claim as new, and desire to secure by Letters Patent, is—

1. In an oil lubricating device, the combination with an oil-reservoir, of a detachable head portion provided with an oil-chamber, an outwardly-extended portion having a channel therein in communication with the oil-chamber, and having a by-path communicat- 55 ing with the upper portion of said oil-chamber, said head having a bridge-wall formed 60

therein, and a steam-chamber disposed above the same adapted to communicate with said by-path, a curved member formed integral with the upper portion of the head having a 65 passage therethrough and a condensing-head formed at the end thereof, means connecting the condensing-head with the outwardly-projecting portion formed upon the head at the lower end thereof and in communication with 70 the channel of the same, and condensing means adapted to communicate with the steam-line and extending through the bridge-wall of the head into the oil-reservoir, substantially as described. 75

2. In an oil lubricating device of the type set forth, the combination with an oil-reservoir, of steam-condensing means adapted to communicate with a steam-line extending into said reservoir, a detachable head portion 80 mounted upon the reservoir provided with an oil-chamber, and a steam-chamber arranged above the same, outwardly-projecting integral members having channels in communication with the oil and steam chambers, means connecting said last-named members forming a sight-feed line therewith, said head portion being further provided with a by-path leading from the upper portion of the oil-chamber and adapted to communicate with the 85 steam-chamber at the opposite side thereof from the sight-feed line, substantially as described. 90

3. In a device of the character set forth, the combination with an oil-reservoir of a detachable head member provided with oil and steam chambers, a sight-feed line in communication with said chambers, means for feeding directly to the steam-chamber from the oil-chamber and steam-condensing means 100 extending through the head portion and into the reservoir, substantially as described. 105

4. In a device of the character set forth, the combination with an oil-reservoir, of a detachable head portion, provided with an oil and steam chamber, a sight-feed line in communication with said chambers, said head being provided with an outwardly-extended portion having a straightway passage therein in communication with the steam-chamber and being further provided with a by-path adapted 110 to communicate with the oil-chamber and with said straightway passage, and steam-condensing means entering said oil-reservoir, substantially as described. 115

In testimony whereof I affix my signature in presence of two witnesses.

JOSEPH V. CLARK.
